CLAIM

The ornamental design for a reader for a payment device, as shown and described.

DESCRIPTION

FIG. 1 is a front view of a reader for a payment device in accordance with our new design;

FIG. 2 is a rear view thereof;

FIG. 3 is a side view thereof;

FIG. 4 is another side view thereof;

FIG. 5 is a top view thereof;

FIG. 6 is a bottom view thereof; and,

FIG. 7 is a perspective view thereof.

The broken line showing the environment is for illustrative purposes only and forms no part of the claimed design.
